W. S. THOMASON

TABLE WITH DETACHABLE TOP

Filed Dec. 24, 1923

Patented Dec. 23, 1924.

1,520,517

UNITED STATES PATENT OFFICE.

WILLIAM S. THOMASON, OF NORFOLK, VIRGINIA.

TABLE WITH DETACHABLE TOP.

Application filed December 24, 1923. Serial No. 682,426.

To all whom it may concern:

Be it known that I, WILLIAM S. THOMASON, a citizen of the United States, residing at Norfolk, in the county of Norfolk 5 and State of Virginia, have invented certain new and useful Improvements in Tables with Detachable Tops, of which the following is a specification, reference being had to the accompanying drawings.

10 This invention relates to tables, and particularly to what are known as pedestal tables which are used for banquets and in hotels and restaurants, the table being such that it may be readily taken apart, knocked 15 down, and stored compactly.

The present invention particularly relates to means for holding the table top upon the pedestal portion of the table, and the general object of the invention is to provide 20 very simple and effective means whereby the table top may be detachably connected with the pedestals, readily applied thereto, or as readily removed therefrom.

A further object is to provide means of 25 this character which is simple, neat, and which is not so evident as to destroy the ornamental effect of the table.

Other objects will appear in the course of 30 the following description.

My invention is illustrated in the accompanying drawings, wherein:

Figure 1 is a top plan view of a table constructed in accordance with my invention, showing in dotted lines the position of the 35 longitudinally extending connecting rail of the table, the table top being partly broken away to show the pedestal and allied parts;

Figure 2 is an end view of the top and pedestal, showing the top before its full 40 engagement with the pedestal;

Figure 3 is a like view to Figure 2 but showing the top plate engaged with the pedestal;

Figure 4 is a vertical sectional view 45 through the upper rail of the pedestal transversely to the length thereof and through the table top, and showing the means whereby the table top and pedestal are connected;

Figure 5 is a face view of the locking 50 strip which is attached to the under face of the table;

Figure 6 is a perspective view of the adjustable bolt whereby the top and pedestal are connected.

55 Referring to these drawings, it will be seen that the table top 10 is supported by means

of two pedestals 11, both of these pedestals being alike and both being provided with a pair of legs 12, the pedestals being connected to each other by means of a longitudinally extending bar 13 whose connections to the pedestals is described and claimed in my pending application for patent filed of even date herewith, Serial No. 682,429.

Each pedestal consists of the two legs 12, a top cross bar 14, and a lower cross bar 15 and a connecting panel 16, though obviously this arrangement may be changed in many ways without departing from the spirit of the invention. The cross bar 14 at opposite points adjacent the legs is longitudinally bored, as at 17, (see Figure 4) the lower end of this bore being enlarged, as at 18. Disposed within and operating in this bore is the bolt shown in Figure 6. The shank of this bolt 19 is circular in form but the upper portion of the bolt is square in cross section, as at 20, and provided with an enlarged head 21. The lower end of the bolt 22 is screw-threaded, and operating in these screw-threads is a nut 23 having a knurled head 24. This nut above the knurled head is formed with a circumferential recess 25 which engages in the semi-circular recess 26 formed in a holding plate 27. This holding plate 27 is attached by screws to the under face of the rail 14. The square portion 20 of the bolt passes through a square opening 28 in a plate 29, and this plate 29 is attached by screws to the upper face of the rail 14. The plate 27 and the plate 29 are both disposed in countersinks formed in the upper and lower edges of the rail 14. It will be seen that with this construction 95 the nut 23 is swiveled within the plate 21 and cannot move up and down and that, therefore, as this nut is turned, the shank 19 will be raised or lowered.

The table top 10, as shown in Figures 4 and 5, is provided on its under face with a transversely extending metallic strip 30, this strip being channel-shaped in cross section and being held to the table top at intervals by screws 31. This strip at two points is 105 provided with the keyhole slots 32, the narrowest portion of each slot being large enough to receive the square portion 20 of the bolt 19, while the widest portion of the slot is sufficiently wide to receive the head 21. 110

With this construction, it is obvious that the table top is intended to be disposed upon

the pedestal with the bolts within the widest portion of the keyhole slot 32, and then the table top may be shifted laterally to carry the heads 21 into the narrowest portions of the slots 32, thus partially locking the table top to the pedestals. After the table top has been slipped laterally into engagement with the bolts 20, the nuts 23 are turned so as to draw the bolt 19 downward and clamp the table top firmly to the pedestals, thus making the table ready for use. It is obvious that by a reverse series of movements the table top may be disengaged from the pedestals and readily removed therefrom.

15 While I have illustrated certain details of construction and arrangement of parts which I have believed to be particularly effective, I do not wish to be limited thereto as it is obvious that many changes might 20 be made in these details without departing from the spirit of the invention as defined in the appended claims.

I claim:

1. In a table, a table top, a pair of supporting members therefor, each including a transverse rail, each rail having a plurality of vertical bores, a pair of strips attached to the under face of the table top and extending transversely thereof, each strip having a plurality of keyhole slots therein, a plurality of locking bolts disposed in the bores of each of said rails, each bolt having a head, the head being adapted to be disposed in the keyhole slot and interlock therewith when the table top is shifted in one

direction, and manually operable means associated with each bolt whereby the bolt may be longitudinally shifted in either direction and held in its shifted position to thereby permit the projection of the heads of the 40 bolts beyond the rails while the table top is being engaged with the bolts and the retraction of the bolts to hold the table top in engagement with the supporting members. 45

2. In a table, a table top, a pair of supporting members therefor each including a transverse rail, the rail having a vertical bore, a pair of strips attached to the under face of the table top and extending transversely thereof, each strip having a plurality of keyhole slots therein, a plurality of bolts disposed in the bores of each of said rails, each bolt having a squared portion and a head, the head being adapted to be disposed within the keyhole slot and interlock therewith when the table top is shifted in one direction, the lower end of each bolt being screw-threaded, a nut engaging the screw-threads, a plate associated with each nut attached to the lower face of the rail, the plate having a recess and the nut being swiveled in said recess of the plate, and a plate attached to the upper face of each rail and having a square opening through which 55 the squared portion of the bolt passes. 60

In testimony whereof I hereunto affix my signature.

WILLIAM S. THOMASON.
